UNITED STATES PATENT OFFICE.

ARTHUR W. CASWELL, OF PHILLIPSBURG, KANSAS.

HORSE-RELEASER.

No. 849,886.

Specification of Letters Patent.

Patented April 9, 1907.

Application filed June 8, 1906. Serial No. 320,958.

To all whom it may concern:

Be it known that I, ARTHUR W. CASWELL, a citizen of the United States, residing at Phillipsburg, in the county of Phillips, State of Kansas, have invented certain new and useful Improvements in Horse-Releaseas; and I do hereby declare the following to be a full, clear, and exact description of the invention, such as will enable others skilled in the art to which it appertains to make and use the same.

This invention relates to vehicles, and more particularly to means for releasing the horses therefrom, and has for its object to provide a horse-releaser which will be simple and which will be arranged to operate efficiently.

It is to be understood that I do not desire to be limited to the exact details of construction shown and described, for obvious modifications will occur to a person skilled in the art.

In the drawings forming a portion of this specification, and in which like numerals of reference indicate similar parts in the several views, Figure 1 is a top plan view. Fig. 2 is a front elevation. Fig. 3 is an elevational view of the mechanism within the wagon-body. Fig. 4 is a section through Fig. 1, taken longitudinally of one of the whiffletrees. Fig. 5 is an enlarged detail view in side elevation of the runner attached to the vehicle-pole.

Referring now to the drawings, there is shown the forward portion of a wagon which includes a body 5 and which is provided with a doubletree 6. A metallic plate 7 is bowed upwardly between its ends, as shown at 8, and has its ends secured upon the whiffletree, the plate lying approximately at the center thereof.

Wings 9 are formed integral with the plate 7 and extend upwardly therefrom at opposite sides of its center, and journaled in the upper ends of these ears there is a horizontal rod 10, connected by means of a universal joint 11 with a rearwardly-extending arm 12, which consists of telescoping members 13 and 14, respectively. A screw 15 is engaged in the outer member 13 and enters the inner member 14 to hold the members at different points of their telescopic adjustment.

A support for the rearward end of the arm 12 is secured within the body 5 and consists

of a hollow upright 16, in which there is mounted for vertical adjustment a rod 17, having a bearing 18 in its upper end which receives the member 13 revolubly therewithin, and a transversely-disposed hand-piece 20 is carried by the rearward end of the member 13. A set-screw 19 is provided to hold the rod 17 at different points of its vertical movement.

Whiffletrees 21 are provided with central openings 22, which align with openings 23 in plates 24, secured upon the whiffletrees, and these openings 22 and 23 receive pivot members 25, by means of which the whiffletrees are connected with the doubletree.

The plate 24 of each whiffletree has a forwardly-extending finger 26, upon which there is pivoted between its ends a lever 27, and a strap 28 connects the upper end of this lever with the rod 10 between the ears 9, there being thus two of these straps 28, and they are connected with the rod 10 in such a way that rotation of the rod in one direction will wind both of the straps thereupon.

Each of the swingletrees has engaged in its outer ends the threaded shank 29 of a forwardly-extending ear 30, and engaged with the whiffletrees inwardly of these ears there are sleeves 31, having forwardly-extending ears 40, which lie parallel with the ears 30. Sleeves 32 are engaged with the ends of the whiffletrees inwardly of and in spaced relation to the sleeves 31 and have forwardly-extending ears 33. The several ears at each end of each whiffletree are provided with alining openings which receive a sliding bolt 34, and these bolts are provided with cross-pins 35 between the ears 33 and 40, each of which rests against one end of a helical spring engaged with its bolt and resting at its other end against the ear 33, the springs being arranged to hold the bolt yieldably with their outer end in the openings of the ears 30.

Rods 36 connect the bolts with the levers 27 at opposite sides of their pivot-points and are arranged to move the bolt against the actions of the springs when the levers are moved through winding of the straps upon the rod 10.

It will be understood that the traces of the team are to be engaged with the bolts 34, and it will be seen that the arm 12 may be revolved to release the team.

The pole of the vehicle is provided with a

runner 37 at its forward end, which strikes the ground when the team is released to prevent the pole from digging into the earth.

What is claimed is—

- 5 A horse-releaser comprising a whiffletree, ears having stems engaged in the ends of the whiffletree, sleeves engaged with the ends of the whiffletree inwardly of the ears, ears carried by the sleeves, a trace-engaging bolt engaged in the sleeves at each end of the whiffletree, for movement into and out of operative position, means for holding the bolt yieldably in operative position, a plate secured upon the whiffletree, a finger carried by the
- 10 plate, a lever pivoted upon the finger, connections between the lever and the bolt for simultaneous movement of the bolt against
- 15

the action of the spring when the lever is moved, a bracket, a rod journaled in the bracket, connections between the rod and the lever for movement of the latter to move the bolts when the rod is revolved, a longitudinally-adjustable arm connected with the rod for rotation thereof, means for holding the arm at different points of its adjustment, 25 an end piece carried by the arm, and a vertically-adjustable support for the arm.

In testimony whereof I affix my signature in presence of two witnesses.

ARTHUR W. CASWELL.
